UNITED STATES PATENT OFFICE.

HARRY R. CANFIELD, OF CLEVELAND, OHIO, ASSIGNOR TO THE ELECTRIC CONTROLLER & MANUFACTURING COMPANY, OF CLEVELAND, OHIO, A CORPORATION OF OHIO.

ELECTROMAGNETICALLY-OPERATED DEVICE.

1,354,882.

Specification of Letters Patent.

Patented Oct. 5, 1920.

Application filed February 16, 1917, Serial No. 149,003. Renewed May 17, 1920. Serial No. 382,083.

To all whom it may concern:

Be it known that I, HARRY R. CANFIELD, a citizen of the United States, residing at Cleveland, in the county of Cuyahoga and 5 State of Ohio, have invented new and useful Improvements in Electromagnetically-Operated Devices, of which the following is a specification.

This invention relates to magnetically operated devices, and particularly to magnetically operated switches.

It is one of the objects of my invention to provide an electromagnetic switch which, when its operating winding is energized 10 above a predetermined value, remains in its normal or open position without restraint due to magnetism produced by the winding, and which closes when the energization of the winding falls to a predetermined value 15 and thereafter remains closed without the assistance of the winding. The switch has mechanical bias both to the open and to the closed position, and the function of the magnetic circuit and its energizing winding is 20 to permit the bias which holds the switch open to act when the winding is energized above a predetermined value, and to bring into action the bias which causes the switch to close and which holds it closed when the 25 energization of the winding is below or is lowered to a point below the predetermined value.

In the drawings, Figures 1, 2, 3, and 4 show side views, partly in section and partly 30 broken away, of three of the many forms in which my invention may be embodied.

Referring to Fig. 1 of the drawings, the energizing winding is shown at 1. The magnetic circuit energized by the winding 1 35 has the vertically movable core or plunger 2, the stationary main frame composed of the right branch 3 and the left branch 4, the armature 5 pivoted at 6, and the stationary pole piece 7. The plunger 2, preferably 40 enlarged at its lower end to increase its weight, is suspended in position by a non-magnetic stem 9, rigidly connected thereto and having at its upper end a head 10 resting upon the finger 11 of the main switch 45 arm 19 to be described. The right branch 3 of the magnetic circuit is preferably restricted in cross section, and is surrounded by a choke sleeve 12 preferably of copper or other material having low electrical resist-

ance. The left branch 4 is preferably not 55 restricted in section. Between the upper ends of the branches 3 and 4 and the pole piece 7 are placed the non-magnetic spacers 13, which may be of brass or similar material. There are provided an air gap 14 between the pole piece 7 and the right-hand end of the armature 5; an air gap 14^a between the upper end of the branch 3 and the armature 5; an air gap 15 between the pole piece 7 and the left-hand end of the 60 armature 5; an air gap 15^a between the upper end of the left branch 4 and the armature 5; and an air gap 16 between the upper end of the plunger 2 and the pole piece 7. The gaps 14, 14^a may be diminished, and 65 the gaps 15, 15^a increased, or vice versa, by means of the non-magnetic adjusting screw 33, whose adjustment may be fixed by the lock nut 34. The armature 5 is normally biased to rotate in a counter clockwise direction, and is stopped by the non-magnetic 70 screw 33 abutting on the pole piece 7.

When the winding 1 is energized, flux generated thereby flows, say upwardly, in the plunger 2 across the air gap 16 into the 80 pole piece 7, tending to lift the plunger: there the flux divides, part going to the right across the gap 14 into the armature 5, back across the gap 14^a, tending to rotate the armature 5 in the clockwise direction, 85 and thence by way of the branch 3 back to the plunger 2; the other portion of the flux flows to the left across the gap 15^a to the left-hand end of the plunger 5 and across the gap 15, augmenting the normal bias and 90 tending to rotate the armature 5 in the counter clockwise direction, and thence by way of the branch 4 back to the plunger 2.

The bracket 17, which carries the pivot 6 of the armature 5, also carries a pivot 18 95 upon which is mounted the main switch arm 19, carrying the switch contact 20. A spring 21 presses on the switch arm 19 at 22, along a line of action slightly above the center of the pivot 18, tending to rotate the switch 100 arm 19 in a clockwise direction. The movement in this direction is limited by the stop 23 on the bracket 17. The finger 11, before mentioned, is integral with the switch arm 19, and has the hole 24 through which the 105 plunger stem 9 passes. When the parts are in the normal, that is, the deenergized, position shown, the weight of the plunger 2 sup-

ported by the head 10 on the finger 11 assists the spring 21 to exert a clockwise torque to hold the switch-arm 19 in its open position against the stop 23.

5 The contact 25, arranged to co-act with the contact 20, is carried by the auxiliary switch arm 26, pivoted at 27 to the bracket 28. The arm 26 is yieldingly urged toward the arm 19 by the spring 29 between the bracket 28 and the arm 26. The clockwise movement of the arm 26 is limited by the finger 31 on the arm engaging the stop 30 on the bracket. Another stop 32 on the bracket is provided to limit the counter-clockwise 15 movement of the arm 26 when the contact 25 is engaged by the contact 20, as will be described.

The operation of my invention is as follows: When the winding is energized with 20 current below a predetermined value, the magnetic flux in the gap 16 lifts the plunger 2 and carries it up into engagement with the pole piece 7. This removes the weight of the plunger from the finger 11, the switch- 25 arm 19 thereafter being held in open position by the spring 21 only. The magnetic flux in the gaps 14 and 14^a overpowers the flux in the gaps 15 and 15^a, and the armature 5 is rotated clockwise about the pivot 6, closing the gaps 14, 14^a. This movement causes a peen 35 on the armature to engage the finger 11 of the switch arm at 36 and to rotate the switch arm 19 counter-clockwise sufficiently to bring the center line of 30 action of the compression spring 21 below the center of the pivot 18. The spring 21 then continues the rotation of the arm 19 and brings the contact 20 into engagement with the contact 25, the contact 25 retreat- 35 ing and compressing the spring 29, securely sealing the contacts with a wiping action. The movement of the contacts is finally limited by the finger 31 striking the stop 32.

By making electrical connections to the 40 studs 37 and 38, which are connected respectively with the brackets 17 and 28, the closure of the contacts 20 and 25 may be employed to close an electric circuit.

When, however, the winding 1 is energized with current above the said predetermined value, the plunger 2 is not only raised, but sufficient flux is generated to satisfy the magnetic capacity of the restricted branch 3, and a greater proportion of the total flux 45 flows in the left branch 4 and exerts sufficient magnetic pull across the gaps 15, 15^a to hold the armature 5 against the opposing magnetic pull in the gaps 14 and 14^a. The choking sleeve 12 on the restricted branch 3 insures against the predominance of pull in 50 the gaps 14 and 14^a during the interval in which the flux is building up to full strength, by momentarily choking the flux out of the restricted branch 3.

65 Upon a reduction of current in the wind-

ing to a point below the predetermined value, the flux in the gaps 15 and 15^a falls more rapidly than that in the gaps 14 and 14^a, and the pull in the gaps 14 and 14^a overpowers that in the gaps 15 and 15^a, whereupon the armature 5 is rotated clockwise and the switch contacts are closed as above described.

After the contacts have closed they remain closed as long as the plunger 2 is held up. 75 If the winding 1 be deenergized, or its energization reduced to a predetermined minimum, the armature 5 will return to its normal position, as shown, and the plunger 2 will fall, causing the head 10 to strike the finger 11 and rotate the switch arm 19 clockwise against the stop 23, thus opening the switch contacts.

The aforesaid predetermined value may be adjusted by adjusting the relative sizes 85 of the air gaps 14, 14^a, and 15, 15^a, by means of the screw 33.

In the form of my invention shown in Fig. 2, the magnetic circuit energized by the winding 40 has the main frame 42, stationary 90 pole piece 43 supported in the main frame by the shoulder 43^a, the plunger 44, the plunger tail piece 45 integral therewith and of restricted cross section, and the magnetic sleeve 46 threaded into the frame 42 at 47 95 and adjustable axially therein. The tail piece 45 carries a non-magnetic sleeve 48 to prevent its sticking to the sleeve 46 when magnetically energized. The axial position of the sleeve may be fixed by the lock nut 100 49. Two gaps are thus provided, the gap 50 between the pole piece 43 and the armature 44, and the gap 51 between the armature 44 and the adjustable sleeve 46. The armature 44 is suspended in position by the 105 non-magnetic stem 52 rigidly secured thereto and passing upwardly through the pole piece 43, and having the head 53 resting on the pole piece. The stem is continued above the head 53, passing through a perforation 110 55 in the finger 56 of the main switch arm 57 and terminating in a head 54.

When the winding is energized, the flux flows, say upwardly, in the armature 44, across the gap 50 into the pole piece 43, 115 and through the main frame 42 to the lower part thereof; there the flux divides, part taking a path upwardly through the sleeve 46 across the gap 51, into the armature 44, and part going directly into the tail piece 120 45 and thence into the armature 44.

The main switch arm 57 is pivoted at 58 to a supporting bracket 59. A spring 60 presses on the switch arm at 61 along a line of action slightly above the center of the 125 pivot 58, giving to the switch arm 57 a clockwise torque holding it against the stop 62 on the bracket. Another stop 63 on the bracket likewise limits the counter clockwise movement of the arm. The upper end of the 130

switch arm 57 carries the contact plate 64 which co-acts with the stationary contact 65, mounted on the supporting bracket 66.

The operation of the form of my invention shown in Fig. 2 is as follows: When the winding 40 is energized with current below a predetermined value, the magnetic pull in the gap 50 predominates over that in the gap 51, and the armature 44 is lifted, carrying upward the stem 52 and the head 53, and causing the latter to engage the finger 56 and rotate the switch arm 57 counter-clockwise sufficiently to cause the line of action of the spring 60 to lie below the center of the pivot 58. The spring 60 then rotates the arm 57 counter-clockwise, bringing the contact 64 into engagement with the contact 65, this movement being finally stopped by the stop 63.

When, however, the winding 40 is energized with current above the predetermined value, the magnetic pull in the gap 51 predominates over that in the gap 50, and the armature 44 is held down. If the current now be reduced to a point below the predetermined value, the pull in the gap 50 will again predominate over that in the gap 51, and the armature 44 will be lifted, and the switch will be closed as above described.

After the switch has closed it will remain closed as long as the armature 44 is held up. When the winding 40 is deenergized, or its energization reduced to a predetermined minimum, the plunger 44 will fall and the head 54 will strike the finger 56 and rotate the switch arm 57 clockwise until the line of action of the spring 60 lies above the center of the pivot 58, whereupon the spring will continue the clockwise movement of the arm, the extent of the movement being limited by the stop 62. The switch contacts are thus opened. If desired, the switch arm may be held in open position by the spring 60 alone, the weight of the armature 44 and its moving system being supported by the head 53 on the pole piece 43 as shown, a small clearance being allowed for this purpose at 67, between the head 54 and the finger 56, when the parts are in the position shown.

In the form of my invention shown in Fig. 3, the magnetic circuit is a modification of that shown in Fig. 1, and has the left branch 72, the pole piece 73 and the weighted plunger 74, energized by the winding 71. The armature 79, pivoted at 76, is overbalanced by the weight 77, tending to rotate it clockwise; and in the normal position, the clockwise rotation of the armature is stopped by the peen 35 engaging the under side of the switch arm finger 11 at 36. The plunger 74 is suspended in position by its non-magnetic stem 9, and the head 10, upon the finger 11, as in Fig. 1, and when in the normal position shown, its weight prevents

the overbalanced armature from rotating the finger 11. A single non-magnetic spacer 75 is used and thus one pair of gaps is provided, the gap 78 between the left-hand end of the armature and the branch 72, and the gap 78^a between the armature and the pole piece 73. The switch arm and the contact members are the same in all essentials as those shown in Fig. 2.

The operation of the form shown in Fig. 3 is as follows: When the winding 71 is energized with current below a predetermined value, the plunger 74 is lifted, removing the head 10 and hence the weight of the plunger 74 from the finger 11; the weight 77 then rotates the armature 79 clockwise, causing the peen 35 to lift the finger 11, giving to the switch arm 57 sufficient counter-clockwise movement to enable the spring 60 to close the switch contacts as described in connection with Fig. 2. When the winding 71 is energized with current above the predetermined value, the magnetism in the gaps 78 and 78^a rotates the armature 79 counter-clockwise until the non-magnetic adjusting screw 33 engages the pole piece 73, thus holding the peen 35 out of engagement with the arm 11. At the same time the plunger 74 is lifted. When the current is lowered below the predetermined value, the weight 77 overcomes the pull in the gaps 78 and 78^a, and rotates the armature clockwise, causing the peen 35 to engage the finger 11, initiating the movement of the arm 57, and causing the switch to close as above described. The contacts remain closed so long as the plunger is held up. When the winding is deenergized or its energization reduced to a predetermined minimum, the plunger 74 falls, and the head 10, striking the finger 11, opens the switch contacts, and also returns the armature 79 to its normal position shown.

In the form of my invention shown in Fig. 4, the magnetic circuit energized by the winding 80 has the main frame 81, the stationary pole piece 82 supported in the main frame by the shoulder 83, the vertically movable plunger 84, and the vertically movable auxiliary plunger 85 preferably enlarged at its lower end to increase its weight. Two gaps are provided, the gap 86 between the pole piece 82 and the plunger 84, and the preferably larger gap 87 between the plunger 84 and the auxiliary plunger 85. The plunger 84 is suspended in position by the non-magnetic tubular stem 88, threaded into the plunger at 89, and passing upwardly through the pole piece 82, and having the head 90 resting on the pole piece. The head 90 continues upwardly, passing between the legs 92 (only one of which is shown) of the fork on the finger 56 of the main switch arm 94, and has the shoulders 95 and 96 above and below the

- finger 56, adapted to engage the legs 92 of the fork. The vertical movements of the plunger 84 cause these shoulders to lower or raise the finger 56. The auxiliary plunger 85 is suspended in position by the brackets 91 engaging the annular shoulder 86 on the plunger. The non-magnetic stem 97 passes through and is vertically movable in the head 90, the tubular stem 88, 10 the plunger 84, and the auxiliary plunger 85, and is normally suspended in position by the collar 98 on the stem, the collar resting upon the upper end of the auxiliary plunger 85. Another collar 99 on the stem 15 97 is normally spaced from the lower end of the auxiliary plunger 85, as shown at 100, and another collar 101 on this stem is normally spaced from the upper end 102 of the head 90.
- 20 When the winding is energized, the flux flows, say, upwardly, in the plunger 84, across the gap 86, into the pole piece 82, through the main frame 81 to the lower part thereof, and upwardly through the auxiliary 25 plunger 85 and the gap 87 to the plunger 84. Under certain conditions of current in the winding, to be described, either the plunger 84 or both this plunger and the auxiliary plunger 85 are lifted and control 30 the operation of the switch members, which will now be described.
- The switch arm 94 and the contact members actuated thereby are the same in all essentials as those shown in connection with 35 the switch arm 57 of Fig. 2, with the following exception: The switch arm 94, besides having the normally horizontal finger 56, has another normally horizontal finger 103. A perforation 104 in the finger 103 40 is located immediately above the upper end of the stem 97, so that, when the switch arm 94 is in the normal open position shown, a vertical movement of the stem 97 will carry its upper end into the perforation.
- 45 The operation of the form of my invention shown in Fig. 4 is as follows: When the winding 80 is energized with current below a predetermined value, the magnetic pull in the gap 86 lifts the plunger 84, closing 50 the gap 86 and carrying the stem 88 and the head 90 upwardly. The shoulder 96 strikes the finger 56 and rotates the arm 94 counterclockwise until the line of action of the spring 60 lies below the center of the 55 pivot 58, whereupon the spring continues to rotate the arm 94 counterclockwise, closing the switch contacts as described in connection with Fig. 2. This movement of the arm 94 rotates the perforation 104 of the 60 finger 103 to the left, and out of the path of the vertically movable stem 97. The continued upward movement of the plunger 84 and the head 90 causes the upper end 102 of the head to engage the collar 101, thereby 65 lifting the stem 97 and with it the collar 99.

which closes up the space 100 and finally lifts the plunger 85. When the gap 86 is entirely closed, and the upward movement of the parts just described ceases, the switch arm 94 is held in closed position by the 70 spring 60 alone, the shoulder 96 not engaging the finger 56 in that position.

When the winding is energized with current above the predetermined value, the pull in the gap 87 is strong enough to lift the 75 weighted auxiliary plunger 85, which in turn lifts the collar 98 and the stem 97, so that when the plunger 84 moves upwardly, the plunger 85 and the stem 97 move with it, the plungers being spaced a constant distance apart by the collar 98. At the first upward movement of the parts, the upper end of the stem 97 enters the perforation 104 in the finger 103. When thereafter the shoulder 96 engages the finger 56 to rotate 80 it counterclockwise, the perforation 104 will tend to rotate to the left, but the right-hand inner wall of the perforation will engage the stem 97 and rotation will be prevented, and the switch will not close, this condition continuing so long as the auxiliary plunger 85 is held up. When the current is reduced to or below the predetermined value, the pull in the gap 87 becomes insufficient to hold the plunger 85, and it falls, first falling 90 freely to close up the space 100, and then giving a hammer blow to the collar 99, which jerks the stem 97 downwardly out of the perforation 104. The switch arm 94 now being free to rotate, the flux in the gap 86 100 continues the upward movement of the plunger 84, and the shoulder 96 on the head 90 causes the switch to be closed as described. The further upward movement of the plunger 84, during the closure of the gap 105 86, again lifts the auxiliary plunger 85 by means of the collar 99, as before described, and holds both plungers up so long as the winding is energized.

As is well known, switches having the 110 general operating characteristics described herein may be used for controlling the starting resistance of an electric motor, and it is, therefore, not deemed necessary to show herein an application of my invention to 115 practical uses. It is apparent that the switches herein described may be substituted for the accelerating switches shown in many motor control systems. For example, my switches may be readily substituted for 120 the accelerating switches shown in my application, Serial Number 583,000, or in Hall's Patent Number 1,197,584.

My invention is not limited in its application to motor control or motor-starting 125 purposes. Many changes and modifications other than those shown may be made without departing from the spirit of my invention; for example, I have shown four forms of magnetic circuit by which the desired 130

characteristics are developed in response to current conditions in the winding, and it will be apparent that other forms of magnetic circuit may be employed. While I 5 have shown the mechanical bias which holds the switch contacts open and the mechanical bias which holds them closed as produced by a compression spring acting on alternate sides of a center of rotation, it will be apparent 10 that other means employing either springs or gravity, or their equivalent, acting without the necessity of magnetic assistance from the winding, may be employed. Other changes and modifications may be 15 made.

I claim—

1. A controlling device for electric circuits containing a winding, a movable switch member, means for biasing the same toward open and closed position from an intermediate position, and means influenced by the current in the winding when below a predetermined value for moving the movable member to such a position in the closing direction that the biasing means may complete the closing movement of the movable member, and when the current is at or above the said value, for preventing the movement of the said member.
2. A controlling device for electric circuits comprising a winding, a movable switch member, means for mechanically biasing the same to both the closed and open positions, and means whereby the bias to open position is overcome and the switch

member closed by its closing bias when the winding is energized with current below a predetermined value, and whereby the bias to open position remains when the current is at or above the said value.

3. A controlling device for electric circuits comprising a winding, a movable switch member, means for mechanically biasing the same to closed position, and means whereby, when the winding is energized with current below a predetermined value only, the switch arm is moved by its bias to closed position, and whereby the switch member remains in closed position when the winding is energized with current above a predetermined minimum.

4. A controlling device for electric circuits comprising a winding, a movable switch member, mechanical means whereby the switch member is moved to closed position, and means whereby the switch member remains in open position irrespective of the magnetism produced by the winding when the current in the winding is above a predetermined value, whereby the switch member is caused to be moved to closed position when the winding is energized with current below the predetermined value, and whereby the switch member remains in closed position when the current in the winding is above a predetermined minimum.

Signed at Cleveland, Ohio, this 13th day of February, A. D. 1917.

HARRY R. CANFIELD.
